(57) **CLAIM**

The ornamental design for the ventilator coupler as shown
and described.

DESCRIPTION

FIG. 1 is a lower right-side perspective view of a ventilator
coupler.

FIG. 2 is a lower left-side perspective view of a
ventilator coupler.

FIG. 3 is a top view of the ventilator coupler; and,
FIG. 4 is a bottom view of the ventilator coupler.

The dashed lines in the drawings illustrate portions of the
ventilator coupler which form no part of the claimed design.
The dot-dash line of FIG. 3 is a boundary line that defines
the bounds of the claimed design and forms no part thereof.

1 Claim, 4 Drawing Sheets
